UNITED STATES PATENT OFFICE.

AUGUSTUS B. DAVIS AND NATHAN H. DAVIS, OF PHILADELPHIA, PA.,
ASSIGNORS OF ONE-THIRD TO LEWIS C. GRATZ, OF SAME PLACE.

CAR-AXLE LUBRICATOR.

SPECIFICATION forming part of Letters Patent No. 280,587, dated July 3, 1883.

Application filed June 24, 1882. (No model.)

To all whom it may concern:

Be it known that we, AUGUSTUS B. DAVIS and NATHAN H. DAVIS, both citizens of the United States, residing in the city and county 5 of Philadelphia, State of Pennsylvania, have invented a new and useful Improvement in Lubricators, which improvement is fully set forth in the following specification and accompanying drawings, in which—

10 Figure 1 is a top view of the lubricator embodying our invention. Fig. 2 is a longitudinal vertical section thereof. Fig. 3 is a horizontal section thereof. Fig. 4 is a transverse vertical section thereof. Fig. 5 is a view of a 15 detached portion. Fig. 6 is a horizontal section of a modification of Fig. 5.

Similar letters of reference indicate corresponding parts in the several figures.

Our invention consists of a lubricator in 20 which the lubricant is fed or supplied to the journal or axle by gravity, thus effectually and continually accomplishing the lubrication.

It also consists of the lid or cover of the journal-box, peculiarly constructed, whereby 25 it firmly retains its position and may be conveniently opened.

It further consists of means for lubricating the end of a journal or axle.

It also consists of a guard for the lid.

30 Referring to the drawings, A represents a journal or axle of usual construction, and B the box thereof. On opposite sides of the box are diagonally arranged tubes or chutes C, which extend from the exterior of said box to 35 the interior thereof, communicating with the latter by means of oblique openings a a in the sides thereof, said chutes being cast with or secured to said sides, and are the recipients of the lubricating material D, which may be of 40 the form of blocks generally known as "hard grease." The space between the journal or axle, and bottom of the box is packed with wool, cotton, or other suitable substance, and also supplied with lubricant, said space being 45 in communication with side spaces of the box, and thus with the chutes C, as more readily seen in Fig. 4. It will be seen that when the lubricant is placed in the chutes C it bears against the journal or axle and remains thereagainst 50 by gravity, so that it is continuously in contact with said journal and axle, and thus effect-

ually lubricates the same, fresh surfaces of the lubricant being presented as it is worn off by the rotation of the journal or axle. Some of the lubricant removed from the blocks is carried around by the journal or axle and directed into the packed space below the same, thus feeding said space and continually lubricating the journal or axle from below. Fresh blocks may be placed in the chutes as required, it 60 being noticed that the expenditure of the lubricant is gradual, and leakage thereof is avoided.

E represents the lid or cover of the box, which is hinged to the front thereof, the guides or journals of the lid entering a vertical slot, b, in the bearing or cheek-piece c of the box, whereby the lid may be raised from its bearing. The lid is of angular or bent form, the upper part being horizontal and adapted to rest on the top of the box. It will be seen 70 that when the lid is raised it is lifted from the top of the box, and may thus be swung outwardly, and thereby opened, the operation being accomplished in an easy and convenient manner. When the lid is to be restored or 75 closed, it is raised above the top of the box, and then permitted to lower thereon, whereby it remains firmly in position, fully closing the front opening of the box. The sides of the lid are extended laterally, forming wings E', which 80 project over the upper or outer ends of the chutes C, whereby provision is made for covering and uncovering said chutes and dispensing with separate lids.

F represents a piece or "brass," which is fitted vertically in the box between the front wall thereof and the adjacent end of the journal or axle, so that said end may bear against said piece F. In order to lubricate the journal or axle at the end just stated, the inner face of the 90 piece F is grooved from the side to the center, forming a duct, d, to which oil or lubricant material may be admitted through the front opening of the box or side chutes, C, the lubricant thus reaching the end of the journal or 95 axle.

In Fig. 6 the duct d extends through the piece F and communicates with a space in the box, said duct and chamber being suitably packed, the lubricant readily reaching the 100 journal or axle through said duct.

Projecting forwardly from the journal-box

are guards G, which are cast with the box, and so disposed that they inclose the sides of the lid, whereby, should the box be struck in the direction of the sides of the lid, the blow will 5 be received by the guards, thus preventing injury or breakage of the lid or of the hinge thereof.

Having thus described our invention, what we claim as new, and desire to secure by Letters Patent, is—

1. A car-axle box provided at its outer end with cheek-piece c, having vertical slot b, in

combination with cover E, having a gudgeon which sets in said slot, said cover resting at its upper end on the top of the box, as set forth. 15

2. The box provided with a chute at its side, in combination with the lid or cover having a lateral extension, substantially as and for the purpose set forth.

A. B. DAVIS.
NATHAN H. DAVIS.
